US00D918502S

(12) **United States Design Patent** (10) **Patent No.:** **US D918,502 S**
(45) **Date of Patent:** **** May 4, 2021**

(54) **VACUUM CLEANER**

(71) Applicant: **Suzhou Jimo Technology Co., Ltd,**
Suzhou (CN)

(72) Inventor: **Chaoliang Ma**, Suzhou (CN)

(73) Assignee: **SUZHOU JIMO TECHNOLOGY CO., LTD**, Suzhou (CN)

(**) Term: **15 Years**

(21) Appl. No.: **29/743,639**

(22) Filed: **Jul. 23, 2020**

(30) **Foreign Application Priority Data**

Jul. 16, 2020 (CN) 202030387883.2

(51) **LOC (13) Cl.** **15-05**

(52) **U.S. Cl.**

USPC **D32/18; D32/21**

CLAIM

The ornamental design for a vacuum cleaner, as shown and described.

DESCRIPTION

FIG. 1 is a perspective view of a vacuum cleaner showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the vacuum cleaner on a cradle.

The broken lines in the drawings are for the purpose of illustrating portions of the vacuum cleaner that form no part of the claimed design. The broken lines showing a cradle in FIG. 9 are for the purpose of illustrating environment and form no part of the claimed design.

1 Claim, 9 Drawing Sheets
